CLAIM

The ornamental design for a sound deadening enclosure for use in transportation units, as shown and described.

DESCRIPTION

FIG. 1 is a top, perspective view of the sound deadening enclosure for use in transportation units, showing my new design;

FIG. 2 is a front elevation view thereof;

FIG. 3 is a top view thereof;

FIG. 4 is a bottom view thereof; and,

FIG. 5 is a side elevation view thereof.

1 Claim, 5 Drawing Sheets
